BUILDING BLOCK CONSTRUCTION

Pierre Jean Rouzaud, Paris, France

Application January 31, 1947, Serial No. 725,673
In France December 8, 1943Section 1, Public Law 690, August 8, 1946
Patent expires December 8, 1963

2 Claims. (Cl. 72—41)

The present invention relates to building block construction.

It is known that the problem of the construction of buildings is aggravated by the difficulty of finding specialized labor, the question of the professional quality and the number of qualified workmen, which are decreasing from day to day. It is therefore of importance that the use of such labor be reduced as far as possible.

The object of the present invention is a new method of construction, resulting from the novel combination of means that are known or not, with a view to rapidly erecting constructions with economy of labor, in comparison with the methods currently in use.

According to the invention blocks are manufactured at the factory, in their final form, the dimensions of which are such that they are convenient to transport and to handle, their weight being for this purpose, with advantage, approximately 15 kilograms and the rapid assembly of which on the building site permits the accurate erection of walls and partitions of the kind which were heretofore realized in an inexact manner by putting into shape, on the building site, the materials necessary for all the various departments of the building art. These materials were used by specialized gangs of professional workmen which had to work on them in order to achieve the dimensions required by the plans and which had to connect together all the various elements constructed with the various materials of all the different departments.

The blocks in accordance with the invention are hollow; they are obtained by molding, with or without pressure, and with or without vibration, in a suitable manner, and they may be reinforced. The material constituting said blocks is preferably a mixture of sand, of small gravel and of cement, when the blocks are to carry loads.

These blocks are laid in the dry state and without the interposition between their beds and joints of any mortar, the presence of the latter, which is always in the form of a layer of a certain thickness, giving rise to imprecision in the erection of the structure. The blocks are assembled by means of keys which have to fulfil the following conditions:

(1) They must be, like the blocks, sufficiently accurate so that the wall and partition faces are sufficiently flat and vertical and do not require any plastering for adjusting and correcting the masonry work;

(2) They must be sufficiently resistant to enable the walls to suitably transmit the loads and overloads they receive. These loads are thus transmitted either horizontally or vertically to the supports or chain bonds constructed to resist the forces resulting from these loads and overloads.

The outer forms of the blocks are strictly those that are necessary to obtain, by simple assembly, in the dry state, without any molding or plastering on the building site, all shapes of building walls and partitions with all their "accidents," such as bay contours, lintels, supports, building frontage projections, bonds, wall and partition angles, etc. This result may be secured by means of a

2

relatively small number of molds, determined in advance, according to the limitations which are imposed on the dimensions of the various parts of the construction. In order to solve the problem of construction generally, it is possible to manufacture a finite number of different blocks which are all multiples of a module, which is that chosen to permit the design of all constructions. By adopting a sufficiently small module to avoid restrictions which are a hindrance from a practical standpoint, 2.5 cms. for example, it is possible, nevertheless, to settle on a number of molds which is satisfactory insofar as the economy of the method is concerned.

The exposed faces of the blocks may be provided at the factory, before being laid on the building yard, with the usual facing materials, such as slab coverings, stoneware, parquet floorings, magnesite flooring, etc. Moreover these blocks may, on demand be bored at the factory to allow passage for the sheaths surrounding piping of all kinds, plumbing, heating, electricity, etc. The accuracy of the holes coupled with the accuracy of the subsequent mounting of the blocks on the building site, renders possible the preparation at the factory of all the pipes, just as all the blocks have been prepared, so that all that remains to be done is to execute on the spot a single job of assembly. It is also possible, if desired, to embed, in the blocks intended for special walls, masses of inert or metallic materials permitting screwing, nailing or otherwise affixing structures to the wall.

The blocks are advantageously manufactured according to mass production principles. This mode of manufacture substitutes industrial molding of basic materials (binder and aggregate or suitable material) for the molding of materials on the building site with the help of binders and aggregates.

The method according to the invention may be associated without difficulty with all the old modes of construction, with or without supporting iron or reinforced concrete frameworks, with or without facings made of ordinary materials (stones, bricks, etc.). Moreover, it allows all outer or inner decorations to be made as well as the affixing of all stone or other facings, the execution of all stucco, ordinary cement, stone-like cement coverings, etc. as well as all plastering and jointing operations.

This method may be carried out in a large number of ways. A certain number of them are illustrated, by way of example, in the accompanying drawings, in which:

Fig. 1 is a perspective view of a basic building block in accordance with the invention.

Fig. 2 is a plan of the same.

Fig. 3 is a perspective view of a connecting key member for blocks of this type.

Figs. 4 and 5 show in plan and side view, from the face side, a variant of the basic block intended for outer walls.

Fig. 6 is a perspective view of a section of wall built with blocks and keys of the kind shown in Figs. 4 and 5.

Fig. 7 is a longitudinal vertical section of a wall construction in accordance with the invention.

Fig. 8 is a vertical cross section taken approximately on the line 8—8 in Fig. 7.

The basic building blocks are made of cement concrete, with or without reinforcement. These blocks are manufactured in the factory in strictly non-deformable molds, of precise dimensions and the setting is effected in a sufficiently constant atmosphere to ensure that the mechanical qualities and the shrinkage of the concrete shall be constant.

The blocks are in the form of a parallelepiped, the dimensions of which are multiples of the module chosen, 2.5 cms. for example; they are hollow and are solely formed of vertical walls, viz: parallel side walls 1, opposed end

walls 2 and a transverse wall 3 parallel to the end walls and midway between them (Figs. 1 and 2). The upper and lower horizontal faces of the blocks are substantially planar and free from any projections that might be chipped or broken off in shipping and handling of the blocks.

The walls and the partitions of the building (the partitions only differing from the walls by their smaller thickness), are constituted by the juxtaposition, without binder, both in the horizontal and the vertical direction of the above-described blocks. In the vertical direction, the 10 superposition is effected by registering of parts.

In the embodiment shown in Figs. 1 and 2, the connection between the various blocks is effected by a key. To this end, the end walls 2 each have in their upper face a recess 4 whilst the mid wall 3 has a similar recess 5 in its lower face. The recesses 4 and 5 have side surfaces which are parallel with the side walls of the block. The recesses preferably have a width not less than their depth and are equidistantly spaced from one of the side faces of the block so that recesses in vertically adjacent blocks will register with one another when the blocks are assembled.

As will be seen from Figs. 6 and 7, the blocks in adjacent courses are staggered so that the ends of the blocks in one course come at the middle of the blocks of the adjacent course. Thus, the abutting end walls 2 of one course register with the transverse partitions 3 of the adjacent course and the recesses 4 in said end walls coincide with the recesses 5 in the partitions. It will further be seen that the end walls 2 of each block in a course register with the transverse partitions 3 of two end-to-end adjacent blocks in the next course. A key 6 (Fig. 3) of right angle parallelepipedal shape is introduced into the recess 5 of a block as well as in the adjacent recess 4 of two neighboring blocks of the lower course and it thus ensures connection of the blocks and correct alignment both in the horizontal and in the vertical direction. This key may be made of cement, steel, wood, or any other suitable material. The keys 6 are accurately made so as to fit precisely in the registering recesses 4 and 5 and thereby lock the blocks against movement out of alignment either transversely or angularly. As there are only two recesses with interengaging keys in any one horizontal face of a block, there is no difficulty in aligning the blocks as they are assembled. If the blocks are laid with the recesses 5 in the partitions 3 up and keys 6 are placed in these recesses, the blocks of the next succeeding course are easily and accurately positioned by engagement of the recesses 4 in their end walls 2 with the keys.

The construction as a whole is ensured by means of two chain bonds, one horizontal and the other vertical. The horizontal and vertical chain bonds may be obtained by means of reinforced concrete. For the vertical chain bonds, it is simply necessary to pour concrete with or without reinforcing rods in the vertically aligned cavities of superposed elements. In order to obtain horizontal chain bonds, the transverse end and central walls of the elements of a course are knocked out for part of their height, starting from the top. Said course is provided, at the bottom of the cut out portion thus obtained, with a horizontal wall and the blocks of the course are filled with concrete with or without reinforcing rods in a manner known per se. These chain bonds serve as beams and posts if the thickness of the walls and their reinforcement are insufficient to withstand the forces imposed on the construction.

As stated above, the vertical elements of the construction, walls and partitions, are produced by the superposition of blocks of the kind described, the dimensions of which are always such that the handling and the laying do not require the use of costly lifting apparatus, or of human efforts that are too exacting. Thus, for example, with a module of 2.5 cm. the height may be 15 cm., the length 30 cm., the thickness, which is greater for walls than for the partitions, may vary between 35 and 5 cm. If

the elements are, as stated above, provided at the factory with glazed earthenware and ceramic slabs, it is preferable to choose for the height and the length of the blocks dimensions corresponding to those of slabs found in the trade or to multiples thereof. The thickness of the walls of the block depends on the loads to be transmitted and on the dimensions of the reinforcements they contain.

Outside walls must be water-tight in case of bad weather. This water-tightness may be obtained in the very simple manner shown in Figs. 4 and 5. On the outer face 1 of the blocks, provision is made on the horizontal and vertical edges of rabbets 8, having a depth varying between 5 and 15 mms. for example, and the grooves thus formed when the blocks are assembled are completely filled with a mortar applied in the cold state which molds itself perfectly into the bottom of the grooves as indicated at 9 in Fig. 8.

It is to be understood that the various elements described above have only been given by way of indication and that many alterations could be made thereto without falling outside the ambit of the invention.

The advantages offered by the method of construction according to the invention, which are a consequence of the industrializing, in the above manner, of the building art, are numerous and may be summarized as follows:

1. Possibility of constructing buildings with extremely variable outer and inner dimensions;

2. Almost complete elimination of specialized labor;

3. Considerable reduction in the time taken for building since:

(a) The labor for working the materials and adjusting them in position on the building site is replaced by factory labor which may be economized and to a great extent replaced by machines, and the building site only requires very limited labor for assembly purposes.

(b) The time taken for adjusting on the yard the carpentry and hardware work is reduced, much of said work being carried out without inconvenience at the factory and the carpentry work, doors and windows, secured at the factory to the frames, being simply mounted in position;

(c) The time lost by the succession at the building site of all the various specialists of the building trade is done away with, since a single gang of workmen is sufficient to ensure the completion of the construction;

(d) There is no time lost in making various holes, seals and connections;

(e) Masonry plasterings being done away with, there is no time lost in drying them;

4. Elimination of all fear of deterioration of the carpentry work during the time when the masonry plastering is being applied;

5. Reduction in the cost price of the building due to the almost complete elimination of the building site running costs, the absolute control of the labor and the elimination of the errors and badly executed work which occur when making use of shapeless materials.

What I claim is:

1. A building construction comprising a plurality of hollow blocks of the same dimensions and shape disposed in predetermined arrangement in horizontal courses in direct edge-abutting relationship and free from bonding material between the abutting edges, said blocks being assembled merely by laying the blocks upon one another

65 in direct contact with one another, said blocks being substantially parallelepipedal in form and comprising spaced parallel side walls and a plurality of spaced vertical transverse walls, the horizontal upper and lower faces of said blocks being planar and free of projections, said blocks

70 in adjacent courses being staggered and being arranged with spaced transverse walls of each block in one course registering vertically respectively with a transverse wall of each of two end-to-end adjacent blocks in the next vertically adjacent course, the contiguous edge portions of said registering transverse walls being provided with reg-

istering recesses extending longitudinally throughout the thickness of said transverse walls and having a width at least as great as their depth, said recesses being equidistant from one side wall and having side surfaces parallel to the side walls of the blocks, and individual keys of right angle parallelepipedal form precisely fitting into said registering recesses and thereby accurately positioning said blocks so that the side walls of said blocks are accurately aligned both horizontally and vertically and said blocks are thereby locked against movement out of alignment either transversely or angularly, there being not more than two recesses and interengaging keys in any one face of a block.

2. A building construction comprising a plurality of hollow blocks of the same dimensions and shape disposed in predetermined arrangement in horizontal courses in direct edge-abutting relationship and free of bonding material between abutting edges, said blocks being assembled merely by laying the blocks upon one another in direct contact with one another, said blocks being substantially parallelepipedal in form and comprising spaced parallel side walls, opposed transverse end walls and a transverse partition wall midway between said end walls, the upper and lower horizontal faces of said blocks being planar and free of projections, said blocks in adjacent courses being staggered and being arranged with abutting end walls of adjacent blocks in one course registering vertically respectively with the transverse partition walls of end-to-end adjacent blocks in the next vertically adjacent course, the contiguous edge portions of said registering transverse walls being provided with registering recesses extending longitudinally throughout the thickness

of said transverse walls and having a width at least as great as their depth, said recesses being equidistant from one side wall and having side surfaces parallel to the side walls of the blocks, and individual keys of right angle parallelepipedal form precisely fitting into said registering recesses and thereby accurately positioning said blocks so that the side walls of said blocks are accurately aligned both horizontally and vertically and said blocks are thereby locked against movement out of alignment either transversely or angularly, there being not more than two recesses and interengaging keys in any one horizontal face of a block.
